UNITED STATES PATENT OFFICE.

WILLIAM P. BETTENDORF, OF DAVENPORT, IOWA.

SIDE FRAME FOR CAR-TRUCKS.

SPECIFICATION forming part of Letters Patent No. 638,902, dated December 12, 1899.

Application filed February 15, 1897. Serial No. 623,390. (No model.)

To all whom it may concern:

Be it known that I, WILLIAM P. BETTENDORF, a citizen of the United States, and a resident of Davenport, in the county of Scott and State of Iowa, have invented certain new and useful Improvements in Side Frames for Car-Trucks, of which the following is a full, clear, and exact description, reference being had to the accompanying drawings and to the 10 letters of reference marked thereon.

The object of my invention is to make a side frame for car-trucks out of one piece of metal and which will be light and strong and durable. This I accomplish by taking a commercial form of beam and cutting away portions of its web and then binding the upper resulting arms at each end downward to the lower resulting arms and suitably connecting them to form a truss-shaped side frame 15 and otherwise complete the same, with the exception of the journal-boxes and other minor details, substantially as hereinafter fully described, and as illustrated in the drawings, in which—

25 Figure 1 is a blank cut from the commercial form of beam, from which said side frame is made. Fig. 2 is a side view of my invention. Fig. 3 is a longitudinal horizontal section through the central portion of the side frame, taken on dotted line 3 3, Fig. 1. Fig. 4 is a vertical transverse section taken on dotted line 4 4, Fig. 1. Fig. 5 is a vertical section through the center of length of the upper flange of the blank, taken on dotted line 30 5 5, Fig. 2; and Fig. 6 is a similar view of the corresponding part of completed side frame, as shown in Fig. 1.

In the drawings, A represents a blank, which is made by taking an I-beam, preferably, of commercial size, and cutting away its web substantially in the following manner, to wit: At the center of length of the beam an oblong opening a is cut in the web, which extends from near the lower flange to 45 a point preferably nearer the upper flange. The vertical side edges of this opening are cut so as to leave a series of two or more lugs b, although the drawings show four on each side, and the lower horizontal edge of this 50 opening a is cut so as to provide a series of lugs, the central one c of which, as shown in the drawings, is longer than the lugs c' c' on

each side of it. The web of the I-beam is also cut away in a corresponding manner on each side of said central opening a to the 55 ends thereof, so as to leave practically an upper and a lower arm d and e, respectively, at each end of the blank, the former of which is slightly longer than the latter. Near the extremities of these arms the web is preferably entirely cut away for a corresponding distance, so as to leave an upper and a lower clip-bar d' and e at each end of the side frame, between which the journal-boxes are secured, as will hereinafter more fully appear. At 60 the root of these clip-bars and between said bars and the vertical edge of the cut-away portion nearest opening a of the blank the arms d and e are each provided with inwardly-projecting web portions f and f', the 65 projection f of the upper arms d extending obliquely downward and toward the adjacent end of the blank and with its end edge at right angles to its oblique sides and the projection f' of the lower arm of the blank extending upward, with its outer edge perpendicular to the lower flange and with its upper edge at right angles thereto.

In converting the blank into a finished side frame the upper arms d of the blank are bent 80 downward until the end edges of the projections f meet and bear against the upper edge of the projection f' of the lower arm, whereupon they are welded or otherwise suitably secured together and the upper clip-bars d' 85 bent parallel to the lower clip-bars. The portion of the flange and web of the beam bounding the upper side of opening a is upset, so as to make it flatter and broader underneath and to give it a longitudinal stiffening-rib on the upper side, as shown in Fig. 6. Thus constructed the buffer-plate x, connecting the upper flanges of the I-beams of the truck-bolster y, will not be sheared in two, as it would be likely to do did it strike directly against the edge of the web remaining after cutting the opening a in the blank A. In completing the side frame the lugs b on each side of opening a are bent laterally, each alternate one being bent inward and the other 95 outward. In cutting these lugs b I prefer to punch a rivet-hole b' through each of them, so that when bent laterally a vertical guide-plate B B can be riveted to said lugs on each 100

side of said opening *a*, so as to enter the grooves of the guide-blocks *X*, secured to the ends of the truck-bolster, and direct the vertical movement thereof.

5 The lug *c* when it is cut is preferably provided with three rivet-holes, as shown, and the lugs *c'* each with one rivet-hole, and when completing the side frame lug *c* is bent horizontally outward and lugs *c'* inward, and the 10 end of the spring-plank of the truck is inserted through opening *a* and rests on and is secured to lugs *c* and *c'* by rivets or otherwise.

The journal-boxes *D* to be used in conjunction with my improved side frames are of any suitable design and are of such dimensions that they fit snugly between the upper and lower clip-bars *d'* and *e'* at each end of the frame. The side of the journal-box facing 20 the center of length of the side frame is provided with two lugs *g g*, one of which is riveted to that part of the web of the frame which in the blank constituted the projection *f* and the other of which is riveted to the part of the 25 blank hereinbefore referred to as projection *f'*. The side of the journal-boxes opposite that from which lugs *g* project has two knuckles *h h*, made integrant with and projecting therefrom, down through which a vertical bolt 30 *E*, whose ends extend through the bars *d' e'*, passes.

Thus constructed I provide a durable side frame for car-trucks which possesses the advantages of a truss, yet is subject to none of 35 the shearing strain to which a truss proper, with its numerous elements, is subject. I do not wish, however, to be confined to the exact construction of either the blank or the side frame as hereinbefore described or 40 shown. The clip-bars, for instance, might be omitted, as likewise the lugs *b* and *c c'*, and a cheaper form of side frame made embodying the principal features of my invention, which consists of making a central opening 45 in a suitable form of beam, the removing of portions of the web, so as to leave two arms at each end of the blank, and the bending of the arms until they meet and then uniting them.

50 What I claim as new is—

1. A blank for side frames for car-trucks, consisting of a beam having a central opening, and portions of the web removed from the ends thereof to near said central opening 55 to form suitable arms, substantially as and for the purpose set forth.

2. A blank for side frames for car-trucks, consisting of a beam having a central opening, and having portions of its web cutaway 60 from the ends thereof to near said central opening to form suitable arms with clip-bars extending from the extremities thereof.

3. A side frame for car-trucks made from a metal beam the web at the center of length 65 of which is cut away to form an opening in combination with a bolster the ends of which

rest in said openings and journal-boxes secured to the ends of said beam.

4. A side frame for car-trucks made from a metal beam portions of the web at each end of 70 which are cut away so as to leave arms which are bent so as to meet and are united together to give a truss shape to the side frame, in combination with journal-boxes secured to the ends thereof.

5. A side frame for car-trucks made from a metal beam portions of the web at each end of 75 which are cut away so as to leave arms, with clip-bars extending from their extremities, which said arms are bent until they meet and are united together, in combination with suitable journal-boxes.

6. A side frame for car-trucks made from a metal beam the web of which at its center of length is cut away, and portions of the web 80 at each end of which are cutaway leaving arms which are so bent as to meet and are united together, in combination with the truck-bolster and journal-boxes.

7. A side frame for car-trucks made from a 85 metal beam having an opening at its center of length made by cutting away a portion of the web thereof, and having portions of the web at each end cut away to form arms which are provided at their extremities with clip-bars: said arms being so bent as to meet and be united together in combination with journal-boxes secured between said clip-bars.

8. Side frames for car-trucks consisting of a metal beam, which in the blank had portions of its web removed at each end so as to 90 leave arms that in the finished frames are so bent as to meet and are united together, and said frames being provided with an oblong opening at their centers of length the vertical side edges of which are provided with a series of lugs that are bent laterally, in combination with journal-boxes secured to the ends of said frames, guide-plates secured to the lugs projecting from the vertical sides of 95 central opening, and the truck-bolster the guide-blocks on the ends of which engage said guide-plates, as set forth.

9. Side frames for car-trucks consisting of a metal beam, which in the blank had portions of its web removed at each end so as to 100 leave arms that in the finished frames are so bent as to meet and are united together, and said frames being provided with a rectangular opening at their centers of length, the lower 105 edge of which is provided with lugs that project laterally, in combination with journal-boxes secured to the ends of said frames, spring-plank connecting said frames and having its ends secured to said lugs, and the 110 truck-bolster having its ends enter and cushioned in said central openings, as set forth.

WILLIAM P. BETTENDORF.
